UNITED STATES PATENT OFFICE

1,989,644

STUFFING BOX AND PACKING THEREFOR

John F. McKee, Lansdowne, Pa., assignor to
Yarnall-Waring Company, Philadelphia, Pa., a
corporation of Pennsylvania

Application October 9, 1931, Serial No. 567,827

1 Claim. (Cl. 285—162)

- My invention relates to stuffing boxes and the packings thereof.
- A purpose of my invention is to charge a stuffing box with plastic or semi-plastic packing through ports located at an end of the box, preferably a plurality of ports entering the box at circumferentially distributed points, with outer portions of the ports conveniently extending inwardly from the outside of a flange.
- 10 A further purpose is to admit packing to a stuffing box through ports extending longitudinally in the gland, so that the portions of the box other than the gland may be made in the usual manner, and so that my method of packing may be applied to existing boxes by merely changing the gland.
- 15 A further purpose is to provide packing for a stuffing box in stick units, for insertion by pumping, preferably ahead of screw operated plungers, a stick unit being dimensioned to adapt it to slip in easily ahead of a plunger when the plunger has been removed without interfering with an easy replacement of the plunger for subsequently forcing the stick into the box as needed.
- 20 A further purpose is to place an inlet fitting on the outer end of an inlet port on a packing gland, so that a pump need only be applied to the inlet when injecting packing.
- 25 A further purpose is to provide a packing compound well adapted to the intended service.
- 30 A further purpose is to provide easy and novel means for adding plastic or semi-plastic packing to a stuffing box without needing to discontinue the service of the pipe or shaft within the box.
- 35 A further purpose is to seat the end flange of a removable gland of a stuffing box against the end of the annulus surrounding the gland, permitting an initial charging of the box with packing with the gland removed, an initial compressing of the charged packing by screwing the gland home to a definite seat where it makes a packing seal with the end of the annulus and to provide for easy subsequent charging of packing through the gland while the gland is in place and without need for interrupting the service of the box or loss of steam or other fluid sealed from escape at the box.
- 40 Further purposes will appear in the specification and in the claim.
- 45 My invention relates to the methods involved and to the apparatus used to carry out the methods.
- 50 I have elected to show a few forms only of my invention, selecting however forms which are practical and efficient in operation and which well illustrate the principles involved.
- 5 Figure 1 is a side elevation of an expansion joint for a steam line or the like and including a stuffing box embodying one form of my invention.
- 10 Figure 2 is a section taken upon the line 2—2 of Figure 1.
- Figure 3 is an enlarged fragmentary section taken upon the line 3—3 of Figure 2.
- 15 Figure 3a is a fragmentary section upon the line 3a—3a of Figure 3.
- Figure 4 is a fragmentary top plan of Figure 3.
- Figure 4a is a section corresponding in position to Figure 3, drawn to reduced scale and showing a variation.
- 20 Figure 4b is a section corresponding in position to Figure 3, drawn to reduced scale and showing a different variation.
- Figure 5 is a view corresponding to a fragment of Figure 2 to enlarged scale and showing a different form from that of Figures 1 to 4.
- 25 Figure 6 is a section taken upon the line 6—6 of Figure 5 or the line 6—6 of Figure 7.
- Figure 7 is a section taken upon the line 7—7 of Figure 6.
- 30 Figure 8 is a view corresponding generally to Figure 2, but drawn to reduced scale, and intended to show conventionally the adaptation of the invention to various types of stuffing boxes, for example those about reciprocating or revolving shafts, plungers, etc.
- 35 Figure 9 is a view corresponding to a portion of Figure 3, showing a different form.
- Figure 10 is a section of Figure 9 taken upon the line 10—10 thereof.
- 40 Figure 11 is a view corresponding generally to Fig. 7, but showing a different form.
- Figure 12 is a perspective view illustrating a set of packing sticks for use with any one of the boxes illustrated in the drawings.
- 45 Describing in illustration and not in limitation and referring to the drawings:—
- The introducing of packing into stuffing boxes has been accomplished in various ways, among others by removing the gland and inserting the packing through the opening left thereby and by pumping in the packing through one or more ports in the outside wall of the box. I have discovered that packing may be satisfactorily inserted through ports in the packing gland itself, without the necessity of altering the construction of other parts of the stuffing box.
- 50 Thus my invention may be applied in existing stuffing boxes by merely changing the packing

gland. Furthermore, I may, if I desire, remove the packing gland and initially introduce the packing into the box in the ordinary manner, then replace the gland and add further packing, 5 without removing the gland, through the ports in the gland.

By introducing a check valve, preferably of stationary type, into the stuffing box at the inner end of each port, packing may be pumped into 10 the box under considerable pressure, preferably from a plunger operating in a cylinder, and the pressure may be released outside the box, as for example, to insert a new packing charge, while maintaining the pressure upon the packing in 15 the box. The check valve of this type is the invention of D. Robert Yarnall, described and claimed in an application copending herewith. The success of a stationary type of check valve when used for this purpose depends upon the 20 highly viscous character of the packing which I employ.

I preferably form my packing into sticks of suitable size for insertion into the pump. Besides being convenient units to handle, the sticks 25 do not require cutting or measuring of the packing for a single application.

While my invention is applicable to stuffing boxes generally, I believe that its widest utility is in expansion joints, because these are ordinarily located in inaccessible places, such as pipe 30 ducts, and therefore the convenience of the means for replacing the packing is at a premium. I will accordingly describe an expansion joint embodying my invention.

35 The joint illustrated in Figures 1 to 4 includes the telescoping inner and outer slides 10 and 11 which present their end flanges 12 and 13 for connection to the corresponding flanges of adjoining piping, not shown.

40 Suitable anchor connections 14 and 15 and a boss 16 for a drain connection may be electrically welded to the outer slide.

The inner slide 10 is externally uniformly cylindrical throughout its length except for the 45 flange 12 at one end and projections, not shown, at the other end that function to prevent inadvertent separation of the slides as in the event of any failure of an anchor that normally prevents longitudinal opening movement of the joint 50 members.

The outer slide 11 provides an annular stuffing box space 17 toward its overlapping end and rearwardly of the stuffing box includes a cylindrical 55 guide 18 that makes a close fit with the outside of the inner slide 10, packing 19 within the stuffing box sealing the joint from the interior of the inner slide along the inside of the cylindrical guide 18.

The cylindrical guide 18 is shown with a considerable portion of its length spaced inwardly at 20 from the main body of the outer slide to which it is rigidly connected at 21 adjacent the inner end of the stuffing box.

The outer slide surrounds my packing gland 65 which forms an end closure of the packing space 17, the gland being shown removable and desirably comprising a flange 22 and an annular portion 23 that may be integral with the flange and fits and extends into the annular packing space 70 17 between the inner and outer slides.

The flange 22 is clamped to the end of the slide body at 24, circumferentially spaced lugs 25 around the end of the slide carrying the clamping bolts.

75 Suitable packing 26 is shown between the end

of the body and the flange. Packing at this point is desirable, but not necessary.

It will be seen that the gland may be used as an ordinary gland when first charging the box with packing, a suitable initial charge of packing being inserted in the open end of the packing space with the gland removed, the gland then being replaced and drawn up strongly until it seats upon the packing 26 against the end of the slide body.

At suitably circumferentially arranged points of the gland I provide passages or ports 27 for delivering packing at distributed points into the stuffing box. The gland is provided with pumps for applying pressure to the packing in the passages 27 as desired.

As illustrated in Figures 1 to 4 the passages 27 include radial bores from the outside of the flange connecting into correspondingly distributed longitudinal bores from the inner end of the gland, the radial bores being shown relatively large to receive bushings 28 that in turn receive the screw-charging pump plungers 29 used to force the packing into the box.

A lip 27' preferably extends across the end of each passage 27. While packing will pass beneath the lip to enter the stuffing box from the passage 27, packing will not pass out from the stuffing box through the passage 27 because the lip 27' covers the end of the passage 27, and the viscosity of the packing is too great to permit of flow of packing around the lip. Thus, though all parts of the end of the port 27 are stationary, the lip 27' acts effectively as a check valve.

There are several ways in which the packing 35 may be initially inserted into my stuffing box. The packing gland may be removed and the box filled with packing in the usual manner to a depth sufficient so that the packing will be under pressure when the gland is bolted into place in 40 the usual way. As an alternative method, the gland may be removed and the stuffing box partially filled with packing, then the gland may be replaced and more packing inserted under pressure from the pump plungers 29. Finally, all of 45 the packing may be inserted through the passage 27 by screwing down the pump plungers 29.

After the joint has been once packed in any one of the ways specified, further additions of packing will preferably be made by screwing down 50 the pump plungers 29, thus forcing packing material from the ports 27 around the lips 27' and into the stuffing box space 19.

When any one of the pump plungers has been 55 screwed fully home, it may be removed without fear of leakage of packing out through the port 27, because leakage is prevented by the curved lip 27'. A new charge may be then inserted in the outer end of the passage 27 and the pump plunger again screwed down to expel packing 60 material into the packing box space 19. The new charge will preferably be added in the form of a stick of suitable size to fit in the outer end of the port 27.

If, due to an emergency, or for any other reason, it be desired to insert braided or other similar packing into the stuffing box, this may be done by backing off the packing gland in the ordinary way. The user of my stuffing box is at no time precluded from changing the form of packing employed.

The number of ports 27 and pump plungers 29 will of course depend upon the size of the joint to be packed and upon the pressure of the fluid medium. In general I prefer to have an 75

even number of ports 27 grouped in pairs, one opposite the other, so that the pressure of packing introduced at any port will be balanced by the pressure of the packing introduced at an opposite port. To maintain this balancing of pressure, the opposite plugs will preferably be screwed in equal amounts at all times and new charges of packing will be introduced in opposite ports at the same time.

10 While it is desirable that pumps be placed at all ports, it will of course be evident that a pump may be temporarily attached to a port in order to apply pressure to the port and then moved to another port. I show in Figure 4a a fitting 15 29' adapted to make contact with a pump external to the gland. The fitting may be provided with the usual ball check, although this is not necessary.

In the form of Figures 5 to 7 the bores for 20 charging are left unthreaded, cylindrical pump plungers 30 and 31 being provided fitting the charging bores 32 and 33 and forced inward by a screw plug 34 intermediate the charging plungers.

25 The intermediate screw plug 34 operates the plungers 30 and 31 by means of a flange 35 below the wrench hold 36, opposite sides of the flange fitting into lateral slots 37 of the charging plungers, and the charging plungers being moved 30 up and down by screwing the plug up and down.

This form is advantageous in that it avoids a relatively rough surface presented to the packing inside the charging passage and also in that the packing sticks are applied in pairs and 35 adapted to move in opposite directions after they enter the box, so that there is no need for any division of a single stick of packing.

The lip 32' (Figure 6) acts as a check valve to the passage 32.

40 In operation, the form of Figure 5 to 7 is similar to that of Figures 1 to 4.

In the form shown in Figures 9 and 10 the charging port 38 divides at its inner end at 39 and 40, thereby dividing the stick of packing 45 so as to enter the stuffing box in two directions.

The sharp end of the abutment 38' assists in dividing the stick of packing.

This form is more desirable when the character of the stick is such as to permit division. 50 If the stick includes long fibers of asbestos or the like, division of the individual sticks is less easy and the form shown in Figure 11 may be used.

Here the ports 41 and 42 upon opposite sides 55 of the screw plug 43 enter the circumferential space in opposite directions. The screwing in of the plug 43 pushes in two sticks simultaneously, which are deflected oppositely at the inner ends of the ports.

60 An important feature of my invention is directed to the packing. I make the packing up in formed sticks 44 of predetermined size to fit the ports ahead of the charging plungers.

The sticks 44 are preferably of a length somewhat less than the range of movement of the 65 screw plungers so that after the plungers have been screwed all the way home and are removed for charging a fresh stick or sticks, the new sticks are not long enough to extend out the 70 charging ports when slipped to place, the sticks

being short enough for the easy entry of the plungers after the stick insertion preparatory to forcing the plungers inward along the ports.

I find that the packing sticks are desirably formed of material that includes long-fiber, high-grade asbestos as a base, with a solid lubricant, which may be soapstone or graphite, either or both, and high fire test mineral oil.

I mix the ingredients, preferably in the proportions by weight of one part of carded asbestos, 10 four parts of pulverized soapstone, three parts of graphite and two parts of heavy oil, and subject them successively to high pressure and high temperature (about 800° F.) as explained in my copending application, Serial Number 15 551,368, for Soapstone, asbestos and oil packing.

A very desirable feature of the invention includes the high pressure gasket joint at 26 between the end of the stuffing box and the gland which entirely eliminates danger of leakage at 20 this point. In practice it has been found hitherto most difficult to keep a stuffing box tight between the outside surface of the gland and the inside surface of the stuffing box, especially in a steam line, due to the tendency of water to 25 make channels in the packing at this point.

While the invention has been illustrated in detail as applied to the stuffing box of an expansion joint, it is also available for all types of stuffing boxes, as for reciprocating or revolving shafts, plungers, etc., Figure 8 being intended to illustrate this conventionally.

In Figure 8 the inner member 10' is the moving member, whether reciprocating or revolving, and details of the anchored outer member 11' may 30 embody corresponding details of any of the described forms.

While the radial direction of the pump plungers is best suited to location of the plungers in the packing gland, it will of course be evident 40 that the plungers need not be radial, so long as they are located so as not to interfere with removal of the gland. In Figure 4b, for example, the plunger extends diagonally.

In view of my invention and disclosure, variations and modifications to meet individual whim or particular need will doubtless become evident to others skilled in the art, to obtain all or part of the benefits of my invention without copying the structure shown, and I, therefore, claim 50 all such in so far as they fall within the reasonable spirit and scope of my invention.

Having thus described my invention, what I claim as new and desire to secure by Letters Patent is:

Means for maintaining the packing of a conventional telescopic pipe expansion joint comprising, in combination with radially spaced outer and inner slides of the joint, which leave an open packing space between the slides, means 60 for tightening a gland, a gland having a sleeve and a flange, being adapted to compress the packing in the box and having a plurality of circumferentially distributed passages through the sleeve for introduction of fluid packing of self-sustaining consistency under pressure when necessary to add packing to the packing space and a plurality of pumps mounted on the flange, one 65 cooperating with each passage.

JOHN F. MCKEE. 70
